COMPRESSOR FOR REFRIGERATING SYSTEMS

John C. Buchanan, Detroit, Mich., assignor, by
mesne assignments, to Borg-Warner Corpora-
tion, a corporation of Illinois

Application October 9, 1933, Serial No. 692,727

8 Claims. (Cl. 230—205)

This invention relates to refrigerating systems of a type generally applicable for employment for domestic and other uses where individual units of relatively small capacity are employed and has particular relation to improvements in the arrangement of parts, the compressing mechanism, and the lubricating features of such systems.

An object of the invention is to provide an improved refrigerating system by co-relating and especially designing the various elements of such systems and whereby there shall be such cooperation between said improved elements as will best serve the purpose of providing an efficient system capable of being manufactured at low cost and of giving the maximum of satisfactory service in use.

Another object of the invention is to provide an improved condensing unit designed for refrigeration purposes which shall have a novel and compact arrangement of parts wherein said parts can be readily assembled and serviced.

Another object of the invention is to provide an improved compressor to be employed in mechanisms for refrigeration purposes, said compressor being provided with certain novel mechanical features whereby the mechanism will operate more quietly and efficiently, and with lubrication and cooling features rendering the compressor more capable of performing its functions in such refrigerating or other mechanisms in which it may be employed.

In the accompanying drawings,

Fig. 1 is a plan view of a condensing unit structure embraced in a refrigerating system and including a compressor;

Fig. 2 is a vertical cross sectional view through the compressor employed in the condensing unit disclosed by Fig. 1 and illustrating the compressor structure as the latter might appear substantially in the plane of line 2—2 of Fig. 1;

Fig. 3 is a longitudinal sectional view through the compressor structure, taken substantially in the plane of line 3—3 of Fig. 2;

Fig. 4 is a cross sectional view of the compressor, taken substantially in the plane of line 4—4 of Fig. 3;

Fig. 5 is a horizontal sectional view taken substantially in the plane of line 5—5 of Fig. 4;

Fig. 6 is a cross sectional view of the compressor, taken substantially in the plane of line 6—6 of Fig. 3 and illustrating the balance weight and oil pump structure embraced therein;

Fig. 7 is a view illustrating the compressor discharge valve and a fragmentary portion of the

compressor in which the valve is employed; the view is taken substantially in the plane of line 1—1 of Fig. 5;

Fig. 8 is a cross sectional view taken substantially in the plane of line 8—8 of Fig. 7;

Fig. 9 is an end view of the compressor structure as the latter might appear in Fig. 1, with the flywheel of the compressor removed therefrom.

The refrigerating system disclosed and embracing the principles of the present invention comprises a frame 23 consisting of pairs of spaced longitudinal metal bars or supports 24 and 25, at the ends of which are employed springs 26, by which the entire condensing unit is suspended by brackets 27, either in a cabinet, or elsewhere, if desired. Rubber washer members 28 are employed at opposite ends of the springs 26 to provide a resilient and relatively noiseless means of attaching the springs to the brackets 20 and longitudinal supports, respectively. Between the longitudinal members 24 adjacent corresponding ends, thereof, there is secured a supporting member 29, preferably constructed of wood or other suitable sound-deadening material, and the opposite ends of which are secured to the longitudinal members by bolts indicated at 31. The longitudinal members are secured together adjacent the ends thereof opposite the supporting member 29 by a metallic supporting member or bar 32, which is considerably narrower than the supporting member 29, and is spaced from the adjacent edge of the latter, a considerable distance, to provide an elongated opening 33. The opposite ends of the supporting member 32 are secured to the longitudinal member 24 by bolts 34.

The condensing unit 20 is driven by an electrical motor 36, secured to the support 29 in any suitable manner (not shown) and is provided with a drive shaft 37, on the end of which a fan 38 and pulley 39 are secured. Both of these elements are secured upon the end of the shaft 37 in such position as to be directly over and to operate partially within the opening 33 between the supports 29 and 32. Driven by the pulley 39 is a belt 41, the opposite end of which engages and drives a combination flywheel and pulley 42, attached to the shaft 43 of a refrigerant compressor 44. The belt 41 may be tightened by the employment of any suitable belt tightening mechanism, such as that indicated at 46.

The compressor 44, which is secured to the support 29 by bolts indicated at 47, comprises a supporting or frame casting 48 having a boss por-

tion 49, which is provided internally thereof with a bearing 51 for supporting the central portion of the shaft 43. Formed at one end of the boss portion 49 beyond the bearing 51 is a relatively large cavity 52, in which a running seal mechanism 53 is supported around a reduced outer end 54 of the shaft 43. Secured to the shaft 43 by pins 56, projecting therethrough, is an annular sealing ring 57, which is seated resiliently upon a gasket 58 abutting a shoulder portion formed between the shaft 43 and the reduced outer end 54 thereof. Abutting the outer surface of the ring 57 is a non-rotatable sealing ring 59, provided with an outwardly projecting flange 61, against the outer surface of which one end of a spring 62 is disposed. The opposite end of the spring 62 abuts and is supported by an annular plate member 63, which in turn is secured upon a gasket 64 by stud bolts 66 projecting through openings formed around the outer edge thereof. Between the outer edge of the non-rotatable sealing ring 59 and the inner edge of the plate 63, is a collapsible bellows 67, the effective cross sectional area of which is substantially equal to the cross sectional area of the sealing edge of the rotatable sealing ring 57. This substantial equality of areas of the two aforesaid elements provides a substantially balanced running seal member, wherein the pressure on the adjacent running surfaces thereof is substantially independent of the fluid pressure internally or externally of the compressor 44, and hence is determined within reasonable limits by the force resulting from the compression of the spring 62. Outside of the plate 63 there is secured around the end of the shaft 43 by one of the bolts 66, an oil trap 68, which cooperates with a disk 69 secured upon the shaft internally thereof for preventing the escape of small quantities of oil, which may be found to leak through the running surfaces of the seal.

On the side of the frame 48 opposite the seal 53, there is secured a relatively large dome or cap 71 which is adapted to provide a compressor chamber or reservoir 72, and in the interior of which a rotary compressor, indicated at 73, is secured. In order to partially cool and to lubricate the compressor 73, the interior of the dome 72 is partially filled with a quantity of oil, indicated at 74, which practically surrounds the compressor and supplies oil thereto through various openings formed therein.

The body of oil 74 also is adapted to lubricate the seal 53 through a duct 76, by which the oil flows from the chamber 72 to the seal chamber 52. The outlet for the oil employed in lubricating the seal within the chamber 52 is provided by a duct 77 communicating at opposite ends with the upper part of the seal chamber and with a pump and balance weight chamber 78 formed between the inner extremity of the bearing 51 and the compressor 73. The oil employed in lubricating the seal is caused to flow through the ducts 76 and 77 and the seal chamber 52 by a combination balance weight and pump 79 which is secured upon the shaft 43 by means of a key indicated at 81. The inner surface of the balance weight and pump member 79 is provided with a large offset balance weight portion, indicated at 82, on one side of the center of rotation thereof, while the opposite surface thereof is so formed as to provide a plurality of radially disposed ribs, indicated at 83, which serve as a centrifugal pump to throw outwardly away from the outlet 75 from the duct 77, the oil which might otherwise

be held against movement in this region. This movement of the oil away from the outlet of the duct 77 causes a continuous flow of oil from the chamber 72, through the duct 76, into and out of the seal chamber 52, and away from the latter through the duct 77. The oil then escapes from the chamber 78 through slots 84 formed in the frame 48 adjacent the parts thereof supporting the compressor 73.

In order to secure the compressor 73 in place, there is provided in the inner wall of the frame 48, an annular groove 86, which is located just outside the chamber 78 and between the latter and the compressor chamber 72. Around this groove there is provided a flange 87, which is internally ground to receive one end of an annular cylinder block 88, in the interior of which the compression chamber is formed. For closing the end of the compressor block 88 adjacent the frame 48, there is provided within the groove, an annular cylinder end wall 89, which is secured in position between the adjacent surfaces of the cylinder 88 and the frame 48. The opposite end of the cylinder 88 is closed by a similar cylinder end wall 91, which is secured in position upon the adjacent end of the compressor block by an end cap 92 having an inwardly projecting annular flange 93 in which the outer end of the cylinder 88 is adapted to closely fit. These several elements of the compressor 73 are secured together and to the frame 48 by bolts 94, which project laterally through openings formed therein and which are secured at their inner ends in threaded openings formed opposite the compressor and within the frame 48.

In order to provide a support for the inner end of the shaft 43, there is formed in the cap 92 a bearing 95 projecting outwardly from the cylinder and supporting an end portion 96 of the shaft 43, which is formed thereon beyond the cylinder. On the end of the reduced portion 96 beyond the bearing 95, there is secured, by a stud bolt 97, a thrust ring 98 which bears against the outer end of the bearing and prevents movement of the shaft in a direction toward the cylinder. The shaft is prevented from movement in the opposite direction by a thrust ring 99 which is keyed upon the shaft, as is indicated at 101, against a shoulder formed adjacent the reduced portion of the shaft 96.

Within the cylinder 88 there is formed upon the shaft 43, an eccentric 102 which is adapted to move within the cylinder upon the shaft between the inner surfaces of the end plates 89 and 91. Considerable space is provided at opposite ends of the eccentric in order to permit oil for lubrication purposes to flow therein and in order to prevent the eccentric from frictional engagement with the end plates. Rotatably mounted upon the eccentric 102 is a rotor 103, the opposite ends of which are adapted to form a close-running fit within a few thousandths of an inch but definitely spaced from the inner surfaces of the end plates 89 and 91. The outer surface of the rotor is adapted to frictionally engage and to roll upon the inner surface of the cylinder in the region directly opposite the portion of the eccentric 102 which lies the greatest distance from the axis of rotation of the shaft 43.

In order to provide lubrication for the rotor, eccentric and cylinder mechanisms, there is formed, within the cap 92, openings 104 which communicate with the space within the chamber 72 occupied by the lubricating oil therein and also with an annular space formed inwardly of

the end plate 91 and around the adjacent portions of the shaft 43. The opposite end of the cylinder communicates with the chamber 78 through similar openings communicating with a similar annular space, formed inwardly of the end plate 89 and around the shaft 43.

In order to make certain that oil is supplied at equal pressure at opposite ends of the rotor and cylinder mechanism, there is formed across the eccentric 102, a longitudinally disposed opening 106 which transmits oil from one end of the eccentric to the other whenever such unequal pressure may exist.

At one side of the cylinder 88 and within the chamber 12, there is provided a laterally projecting boss 107 in which is formed a transversely disposed cylindrical opening 110 and which in turn communicates along the inner edge thereof with a rectangularly shaped slot 108, the opposite end 15 of which terminates within the inner surface of the cylinder. In this slot is disposed, in sliding relation to the opposite surfaces thereof, a reciprocating blade 109, the inner end of which is cut 20 off angularly, as is indicated at 111, to provide an end 112, which engages the edge of the rotor 103 as the latter is moved by the rotation of the eccentric 102. The end 112 preferably is provided 25 with a convex surface upon which the oppositely curved surface of the rotor is adapted to 30 move.

In order to hold the blade 109 in contact with the rotor 103, there is provided a spring 113, the opposite ends of which are secured by screws 114 to one side of the boss 107 directly opposite the opening 110 formed therein. An intermediate portion of the spring 113 is formed to provide a laterally projecting tongue 116, which extends inwardly of the opening 110, and there is seated, adjacent the central portion of the blade 109 in a semicylindrical slot 117 formed along the edge thereof.

In order to provide an inlet for the compressor, there is formed on the outer surface of the frame 48 an elongated boss 118 on the outer end of which is provided a flange 119, to which the suction line 45 shut-off valve mechanism 121 of the system is adapted to be secured. Formed in the boss 118 and communicating with the suction line of the system at one end is an inlet duct 122, the inner 50 end of which terminates in a laterally extending duct 123, extending inwardly of the frame 48 and within the cylinder block 88. The inner end of this duct communicates with the lower end of a suction passage 124, extending downwardly with- 55 in the central portion of the block from an inlet opening formed immediately below the inner edge of the blade 109. As the rotation of the cam 102 causes a rotational movement of the rotor 103 within the cylinder 88, the refrigerating fluid 60 employed within the system is drawn within the cylinder to fill the progressively enlarging space between the cylinder and the rotor.

As the shaft and eccentric continue in rotational movement, the fluid thus drawn within the cylinder eventually becomes compressed by the rotor against the surface of the blade 109 opposite the inlet passage 124, and in order to provide for the discharge of compressed fluid from this region, there is formed in the cylinder a laterally disposed arcuate slot 126, extending substantially from one side of the cylinder to the other and communicating with the cylinder along the inner surface of the blade slot 108. The discharge passage 126 has a laterally disposed enlarged portion 127 formed at the end thereof adjacent the end

plate 109, which communicates through a passage 131 with a discharge chamber 133 formed in the compressor wall between the adjacent surfaces of the cap 92 and the end plate 91. In this chamber there is secured, by a screw 134, a reed discharge valve 136 having a resilient end portion remote from the screw 134 disposed over the outer end of the passage 131, in such manner as to resist the flow of fluid therefrom. Disposed in a cylindrical portion 137 of the discharge chamber 133, located opposite the passage 131, but offset somewhat at one side thereof, is a short coil spring 138, one side of which rests upon the end of the reed 136 and over the passage 131. With the spring and reed thus disposed in unbalanced relation, the reed tends to be twisted upon its seat over the end of the passage 131 whenever the pressure within the cylinder is increased to such an extent as to overcome the combined forces of compression within the reed and spring 138. In this manner the gas is discharged from the cylinder without appreciably raising the reed from its seat upon one edge thereof, and hence the gas will pass quietly out into the discharge chamber 133. From this region, the gas is discharged into the chamber 12 inside the dome 71 through a curved conduit 139, the upper end of which terminates within the dome above the level of the oil contained therein.

It will be observed that the high pressure gas within the dome 71 will maintain a flow of oil inwardly through the moving parts of the compressor and across the frictionally engaging surfaces between the opposite ends of the rotor 103 and the inner surfaces of the end plates 89 and 91, toward the suction side of the compressor. In this manner the compressor is kept constantly lubricated, and a running oil seal is formed at the opposite ends of the rotor which prevents the leakage of gas from the high to the low sides of the compressor.

The gas, after being discharged into the upper part of the dome by the conduit 139, is permitted to escape from the dome through a duct 141 formed in the upper part thereof and extending outwardly of the dome through a boss 142, formed thereon. To this boss is attached a high pressure line cut-off valve 143, from which the gas is transferred by a conduit 144 to the upper part of a condenser 146, which is secured upon one end of the support 32 directly in front of the fan 38. From the bottom portion of the condenser, the condensed refrigerant is discharged through a conduit 147 into the upper part of a liquid receiver 148 which is secured also to the support 32 beside the condenser 146 and directly in front of the drive shaft of the compressor 44. 45 50 55

From the lower part of the receiver 144, liquid refrigerant is discharged through a shut-off valve 149 and a conduit 151 into a suitable evaporating unit.

It will be understood that the structure illustrated only represents a preferred form of the invention, the scope of which is indicated by the appended claims.

I claim:

1. In a refrigerating system a refrigerant compressor associated therewith, said compressor being provided with a chamber into which said compressor discharges and which forms a refrigerant and lubricant reservoir, a shaft projecting into said chamber below the lubricant level therein and having a running seal associated therewith, said seal being disposed in a region remote from said chamber, and means associated with said 75

- shaft for circulating a continuous stream of lubricant under pressure from said chamber within the space surrounding said seal and thereafter returning said lubricant to said chamber.
5. 2. In a refrigerating system a compressor associated therewith, said compressor being provided with a lubricant and refrigerant receiving chamber into which said compressor discharges and having a bearing at one side thereof below the lubricant level therein, a shaft journaled in said bearing for operating said compressor, said shaft having a running seal associated therewith upon the end thereof remote from said chamber and beyond said bearing, said seal being provided 10 with a seal chamber adjacent said bearing in open communication with said refrigerant and lubricant chamber, and a pump operatively associated with said shaft for circulating a continuous stream of lubricant under pressure between said 15 two chambers and over said seal.
3. In a refrigerating system a compressor having a bearing block, said bearing block being provided with a laterally projecting annular flange formed at one side thereof, a stationary cylinder block disposed on one side of said bearing block 20 and having an annular exterior surface adapted to fit within the interior surface of said flange, a shaft journaled within said bearing block and projecting within said cylinder block, means for rigidly securing said cylinder block to said bearing block, pumping mechanism associated with said shaft and cylinder block whereby refrigerant fluid is compressed in said cylinder block and discharged externally thereof, and a dome surrounding 25 said cylinder block and pumping mechanism for receiving the fluid compressed thereby.
4. In a refrigerating system a compressor, said compressor being provided with a bearing block having a laterally projecting annular flange formed on one side thereof, a cylinder end plate 30 disposed within said flange, a stationary cylinder block having an annular exterior surface adapted to be disposed against the exterior surface of said cylinder end plate and within said annular flange, a shaft journaled in said bearing block and projecting through said cylinder block, means for rigidly securing said cylinder block and cylinder end plate to said bearing block, means associated 35 with said shaft and cylinder block for compressing refrigerant fluid and discharging said fluid externally of said cylinder block, and means for receiving the compressed refrigerant fluid 40 discharged from said cylinder block.
5. In a refrigerating system a compressor, said compressor being provided with a cylinder block having annular end portions, a pair of end plates disposed against said annular ends of said cylinder block, a pair of end members disposed against the exterior surfaces of said end plates 45 and being provided with annular flanges surrounding the edges of said end plates and engaging the exterior surface of said cylinder block 50

adjacent the opposite ends thereof, pumping mechanism disposed within said cylinder block and adapted to compress the fluid employed in said system and to discharge said fluid externally of said block, and a dome surrounding said cylinder block and secured to one of said end members for receiving said compressed fluid. 5

6. In a refrigerating system, a compressor comprising a bearing block, a shaft journaled in said block, oppositely disposed recesses in said block about said shaft, sealing means associated with said shaft and disposed in one of said recesses, a dome secured to said block adjacent the other of said recesses and providing a lubricant and refrigerant reservoir, compressor means associated with said shaft within said dome and operable for compressing a gaseous refrigerant and discharging the same into said dome, a passageway affording communication between said recesses, passageways between each of said recesses respectively and said reservoir, and lubricant pumping means disposed in said recess opposite to that in which said sealing means are disposed for circulating lubricant from said reservoir over said sealing means. 15

7. In a refrigerating system a compressor, said compressor being provided with a bearing block, a cylinder end plate disposed against said bearing block, a cylinder block having an annular exterior surface adapted to be disposed against the exterior surface of said cylinder end plate, a recess in said bearing block adjacent said cylinder end plate, a shaft journaled in said bearing block and projecting through said recess in said bearing block, means associated with said shaft and cylinder block for compressing refrigerant fluid and discharging said fluid externally of said cylinder block, and a counterweight for said compressing means disposed within said recess. 30

8. In a refrigerating system a compressor, said compressor being provided with a bearing block, a cylinder end plate disposed against said bearing block, a cylinder block having an annular exterior surface adapted to be disposed against the exterior surface of said cylinder end plate, a recess in said bearing block adjacent said cylinder end plate, a shaft journaled in said bearing block and projecting through said recess in said bearing block, a running seal associated with said shaft and disposed adjacent the opposite side of said bearing block, means associated with said shaft and said cylinder block for compressing refrigerant fluid and discharging said fluid externally of said cylinder block, a dome secured to said bearing block and providing a lubricating oil and refrigerant chamber surrounding said compressor, and pumping means within said recess for circulating lubricant from said chamber within the space surrounding said seal and thereafter returning said lubricant to said chamber. 45

JOHN C. BUCHANAN. 55
